FIG. 11.

FIG. 12.

UNITED STATES PATENT OFFICE

2,170,362

SAFETY DEVICE FOR CASH REGISTERS OR
THE LIKE

Erazm Zoub, New York, N. Y.

Application May 5, 1937, Serial No. 140,926

3 Claims. (Cl. 109—46)

My invention relates to safety devices, and more particularly has reference to safety devices for the safeguard of money or other valuable articles against robbery in the event of a holdup or an attempted holdup. While I have shown my inventive concept used in connection with a cash register, and a bank counter, it is of course to be understood that my invention is of much broader application.

10 I am, of course, cognizant that various devices have been proposed for the protection of cash registers against such criminal practices. These protective devices, however, have not proven entirely satisfactory. The majority of these prior 15 devices have been somewhat complicated in construction and operation, and the cost of manufacture renders the use of the same prohibitive.

An important object of my invention is to overcome the disadvantages now present in the art.

20 An object of my invention is to provide a safety device for cash registers and the like, which can be cheaply and easily manufactured.

Another object of my invention is to provide a device for cash registers and the like which will 25 normally give free access to the money or other articles deposited therein and yet which will deposit the articles in a vault in the event of a holdup.

A still further object of my invention is to 30 provide a safety device for cash registers and the like which is simple and sturdy in construction, and positive in operation.

Yet another object of my invention is to provide a cash register and the like with a vault 35 and means whereby the vault cannot be opened until the expiration of a predetermined period of time.

With these and other objects in view, which may be incident to my improvements, the invention consists in the parts and combinations to be hereinafter set forth and claimed, with the understanding that the several necessary elements comprising my invention may be varied in construction, proportions and arrangements, 45 without departing from the spirit and scope of the appended claims.

In order to make my invention more clearly understood, I have shown in the accompanying drawings means for carrying the same into practical effect without limiting the improvements in their useful applications to the particular constructions which, for the purpose of explanation, have been made the subject of illustration.

In the drawings:

Figure 1 is a view in perspective showing the preferred embodiment of my invention.

Figure 2 is a sectional view taken through the center of the device shown in Figure 1.

Figure 3 is a view taken along line 3—3 of Figure 2.

Figure 4 is a view taken along line 4—4 of Figure 3.

Figure 5 is a view in perspective showing my novel latch construction.

Figure 6 is a view in perspective of a retaining strip of fusible material.

Figure 7 is a diagrammatic representation of the wiring circuit used in connection with the device shown in Figures 1 to 6, inclusive.

Figure 8 is a fragmentary sectional view similar to Figure 4 showing another manner of operating my device.

Figure 9 is a diagrammatic representation of the wiring circuit used in connection with Figure 8.

Figure 10 is a view in perspective partly cut away, showing fluid actuated means for operating my device.

Figure 11 is a view in perspective partly broken away, showing my invention used in connection with a bank teller's counter.

Figure 12 is a sectional view taken through the form of my device shown in Figure 11.

Figure 13 is a view taken along line 13—13 of Figure 12.

Figure 14 is a diagrammatic representation of the wiring circuit used in connection with the device shown in Figures 11 to 13, inclusive.

Figure 15 is a diagrammatic representation of the wiring circuit similar to Figure 14 in which a main vault is used.

Referring to the drawings, and more particularly to Figure 1, I have shown a conventional cash register 1 suitably mounted upon a cabinet structure 2.

Referring to Figure 2, it can be seen that the lower portion of the cabinet 2 is provided with a deposit chamber or vault 3. The vault 3 is provided in its upper face with an aperture 4.

An inclined slide 4' is suitably secured at its upper end to the interior of the cabinet 2. The lower end of the slide is secured to the upper wall of the safe 3 adjacent the aperture 4. An arcuate slide 5' is secured to the cabinet and extends through the aperture 4 and into the interior of the safe 3 as shown in Figure 2.

As will hereinafter become more apparent, when articles are deposited on the slide 4' they will move down the same, through the aperture

4, onto the slide 5' whence they will move into the vault 3.

Hinged to the front of the vault 3 is a door 5 provided with an operating handle 6. The door 5 is provided with a time lock mechanism (not shown) which may be of any desired construction. The lock mechanism may be set to release the safe lock at the expiration of a predetermined time.

10 As shown in Figure 1, the top of the cabinet 2 is provided with a rectangular aperture 7. Positioned immediately beneath the aperture 7 is a till or the like 8, employed for the reception of money or other valuables. A flexible closure member 9, having a grip member 10 is adapted to close the aperture 7. As shown in Figures 2 and 3, the flexible member 9 moves between the outer wall of the cabinet 2 and channel members 11 suitably secured to the side walls of the cabinet. Resilient means, such as a coil spring 12, having one end secured to the flexible cover 9, as at 13, and having the other end secured to the vault 3, as at 14, is provided to normally hold the cover 9 in an open position.

25 Referring to Figure 2, it can be seen that the flexible cover 9 carries an arm 15, provided with a latch 16 at its free end. The latch 16 is adapted to cooperate with the cash register mechanism (not shown), so that when a sale is rung up, 30 the latch 16 will be released, thereby permitting the cover 9 to be pulled open by the action of the spring 12.

When it is desired to close the cover 9, the operator merely grasps the grip member 10 and 35 manually moves the closure to the position shown in Figure 2. The latch 16 will then again be engaged with the register mechanism and the closure 9 will remain in its closed position until a sale is again rung up.

40 As shown in Figures 2 and 3, the till 8 is provided with a compartment for bills and a compartment for silver, designated 17 and 18 respectively. The compartments 17 and 18 are provided with lower closure members 19 and 20. 45 The closures 19 and 20 are suitably affixed to arms 21 and 22 respectively. The arms 21 and 22 are mounted on shafts 23 and 24 which are pivotally mounted in side partitions 25 suitably secured to the interior of the cabinet 2.

50 It is, of course, to be understood that the till 8 shown in the drawings is merely illustrative, and any type of till may be employed. For example, the till could be provided with a single lower closure member, thereby necessitating the use 55 of a single arm and a single shaft.

It can be seen from Figures 3 and 4 that the shafts 23 and 24 are provided with arms 26 and 27 at one of their outer ends. The other end of each of the shafts 23 and 24 is provided with a collar 60 28. A link 29 pivotally connects the arms 26 and 27 so that they will move in unison.

Suitably affixed to the partition 25 is a block 30 of suitable insulated material. A bell crank latch 31 is pivotally mounted on the block 30 as 65 at 32. The latch 31 is adapted to engage a catch formed at the end of the arm 26 when the safety device is in the inoperative position. A spring 33, having one end affixed to the bell crank latch as at 34, and having the other end 70 affixed to the block 30, as at 35, normally tends to hold the latch 31 out of engagement with the arm 26.

A retaining strip of fusible material 36 having a reduced portion 37 has one end secured to the bell crank latch 31 by a binding post 38. The

other end of the strip 36 is secured to the block 30 by a binding post 39. A lead wire 40 attached to the latch 31 is held to the insulated block by binding post 41. A lead wire 42 is secured to the strip 36 by the binding post 39.

A plurality of switches 43 are interposed in the circuit in various locations throughout the business establishment so as to permit the easy operation of any of the switches in the event of a holdup or an attempted holdup.

10 The operation of my system may be best understood by reference to Figure 7. In the event of a holdup, by depressing any one of the switches 43, current will flow through lead 42, the bell crank latch 31, and the retaining strip 36. The 15 current will also flow through lead 40, switch 43, lead 44, lead 45, and thereby actuate an electromagnetic device 46, operating a pivoted armature 47 starting time lock mechanism 113. The current also flows from switch 43 to the retaining 20 strip 36.

The current flowing through lead 42 and the latch arm 31 will blow out the reduced area 37 of strip 36. This will break the retaining strip for the latch 31, and spring 33 will move the latch about its pivot 32, freeing arm 26 therefrom. Arms 26 and 27 will then fall, and at the same time cause the bottom closure members 19 and 20 of the till 8 to fall. The money or other valuables deposited in the till 8 will then fall upon the slide 4', onto the slide 5' and into the safe 3.

Inasmuch as the time lock mechanism 113 has also been started, the vault 3 cannot be opened until the expiration of the time for which the mechanism was set.

As shown in Figure 1, I provide a door 47' in the upper portion of the side wall of the cabinet 2, for permitting access to the interior of the 40 cabinet to repair or replace any of the parts of the latch mechanism.

50 It will be readily appreciated from the foregoing description that I have devised a safety device for cash registers which includes few 45 working parts, and which is positive in operation. Moreover, having a vault included in the structure, it is not possible to remove any valuables from the device until a certain predetermined period of time has transpired.

In Figures 8 and 9 I have shown another form of safety device which may be used. In this form the arm 26 carries a segmental gear 50 at its free end. The gear 50 is adapted to mesh with a worm 51 carried by the motor shaft 52 of a suitable 55 electric motor 53.

Suitably mounted on the wall of the cabinet is a support 54 carrying a switch 55. The switch 55 comprises resilient arms 56 and 57 carrying suitable contact points 58. The arm 57 is of 60 such length as to be contacted by the link 29 as will hereinafter be described. Leads 40 and 42 are connected to the contact support arms 56 and 57 respectively.

65 By the depression of any of the switches the current will flow through lead 40, switch 43 and contact arm 56. The current will also flow through lead 42, motor 53, and arm 57. When the motor is energized, the worm 51 will drive the segmental gear 50 which will in turn move 70 the link 29 towards the right and contact the arm 57 thereby breaking the circuit to the motor 53. At the same time the electromagnet means 46 will be energized starting the time lock mechanism 113.

There is shown in Figure 10 another form of my device in which a source of fluid under pressure is employed to operate the lower closure of the money till.

5 The free ends of the arms 26 and 27 are pivotally mounted to a link 70 as shown at 71 and 72 respectively. The link 70 in turn is pivotally mounted to a link 73. A piston 74 operating in a cylinder 75 is pivotally connected to the link 10 73 by a pivotal connection 77.

A supply cylinder 78 positioned in any suitable location, carries a source of fluid pressure. Piping 79 is suitably connected to the cylinder 78 for conducting the liquid to the cylinder 75.

15 In order to regulate the flow of the fluid to the cylinder 75, I provide a plurality of valves 80 which may be interposed between the supply cylinder 78 and the cylinder 75. Branch pipes 80 connect the main pipe line 79 with each of the valves 80. The valves 80 are provided with an operating handle 81. A branch pipe 82 connects each of the valves 80 with a pipe 83 which is in communication with the cylinder 75.

20 The operation of this system is believed to be readily apparent. By actuating any one of the valves 80, fluid is admitted into pipe 83, thence into the cylinder 75 moving the piston 74 which in turn moves arms 26 and 27 through the links 70 and 73 thereby causing the lower closures 19 and 20 to fall and deposit the money into the vault 3.

25 In Figures 11 to 15 inclusive, I have shown my device used in connection with a bank counter. Referring now to Figures 11 and 12, I have shown a bank counter designated 90. A plurality of money tills 91 are provided in the top of the counter. The counter 90 is also provided with the usual glass front 92.

30 The arms 26 and 27 connected to the lower closure of each till are pivotally mounted to a connecting link 94. The link 94 carries a latch 95 at its extremity. The latch 95 is adapted to cooperate with the bell-crank latch 31. The bell crank latch and its associated elements are of 35 the same construction as those shown in Figures 1 to 6, inclusive, and it is not believed necessary to go into a detailed discussion of the same.

35 The insulated block 30, however, is suitably secured to the upper closure of the counter 90 by means of supports 96.

40 Suitably affixed to the rear wall of the counter 90 is an angularly disposed slide 97. Secured to the front wall of the counter is a slide 98 of arcuate configuration. Positioned immediately 45 beneath the slide 98 and cooperating therewith is an endless conveyer 99 which may be of any desired construction. The conveyer is of such length as to be positioned beneath all of the tills 91.

45 As shown in Figures 11 and 13, a vault 100 is provided at the end of the counter 90. The conveyer 99 communicates with the vault 100 through an opening 101. A door 102 provided with a time lock (not shown) is hinged to the front of the vault 100. Positioned immediately 50 above the door 102 is a door 103 which permits access to the bell crank latch construction.

55 The operation of this system is similar to the device shown in Figure 6. When any one of the switches 43 is depressed, the current will flow through lead 42, the bell crank 31 and the fusible retaining strip 36. The current will also flow through lead 40, switch 43, lead 104 to the retaining strip 36.

60 The current will also flow through lead 42.

lead 105 and actuate relay 106 which operates a pivoted armature 107 to complete the circuit to one side of a motor 108. The current also flows through lead 40 and lead 109 completing the circuit to the other side of the motor 108. The motor 108 thus energized causes the conveyer 99 to move.

65 As the latch releases the arm 26, it causes the lower closure members of each of the tills 91 to fall, thereby depositing the money onto 10 the slide 97. The money moves down slide 97 onto slide 98 and is from there deposited onto the conveyer 98. The conveyer moves the money toward the vault and deposits it therein through the aperture 101.

70 The current also flows through lead 42 to one terminal of an electromagnet 46. The current also flows through lead 40, switch 43, lead 104, and lead 111 to the other terminal of the electromagnet 46 thereby actuating a pivoted armature 112 to start the mechanism of the time lock in the door 102.

75 The circuit shown in Figure 15 is identical with that shown in Figure 14 with the exception that the conveyer 99 moves the articles to the main vault of the bank.

80 While I have shown and described my safety device in connection with a stationary money till, it is of course apparent that my invention is of broader scope. For example, the money till 30 may be of the conventional type, that is, the drawer moves back and forth. When such a movable drawer is employed, the elements for actuating the pivoted lower closure would be 35 suitably carried by the side wall of the till.

85 It will be appreciated that this type of money till will be just as efficient and easy to operate as the stationary money drawer. As soon as the switch is closed, the pivoted lower closure will fall, thereby depositing the valuables within the 40 safety vault.

90 From the foregoing it is believed apparent that I have devised a safety device for various types of money tills which is highly efficient and cheap to manufacture. Moreover the device does not 45 in any way affect the normal operation of the money till, but by the actuation of a suitably located control, it will deposit the articles disposed in the till into a vault or similar depository. Furthermore by having a time lock mechanism included in the door of the vault, it is impossible to open the door until the expiration of 50 a predetermined period of time.

95 It is to be understood that the form of invention herein shown and described is to be construed as a preferred embodiment of the same and that any changes and variations may be resorted to without departing from the spirit of the invention or exceeding the scope of the appended claims.

100 I claim:

1. In a remote control depositing money container, a till, a vault positioned substantially below the till, a downwardly movable bottom for the till, a member spaced apart from and concurrently movable with said till bottom, said member being positioned in the vault and to one side of said till bottom, said member and said till bottom being gravity urged to a position whereby any objects contained in the till will be 70 released into the vault, means positioned in the vault for resisting movement of said member and said till bottom into releasing position, said resisting means normally engaging said member, said resisting means being movable out of the 75

path of said member, means for constantly urging said resisting means through its path away from resisting position into releasing position, a fusible link adapted to be weakened past the breaking point by the passage of electricity therethrough, said link normally preventing movement of said resisting means from its resisting position, whereby an electric current may be utilized to release the resisting means to permit objects in the till to fall into the vault.

5 2. In a remote control depositing money container, comprising a till, a vault positioned substantially below the till, a plurality of downwardly swingable bottoms for the till, shafts turning with said till bottoms, arms in parallel relationship attached to said shafts at one side of said till bottom and at an angle below that of said till bottom when said till bottom is at its uppermost position, a connecting rod between said arms whereby said shafts and said arms move concurrently, said arms and said till bottoms being gravity urged to a position whereby any objects contained in the till will be released into the vault, 10 means positioned in the vault and engaging one of said arms for resisting movement of said arms into releasing position, said resisting means being movable out of the path of said arm, the path of movement of resisting means diverging 15 from the path of movement of said arm as said resisting means moves away from resisting position, means for constantly urging said resisting means through its path away from resisting position into releasing position, a fusible link adapted to be weakened past the 20 breaking point by the passage of electricity therethrough, said link normally preventing movement of said resisting means from its resisting position, whereby an electric current may be utilized to release the resisting means to permit objects in the till to fall into the vault.

25 30

be utilized to release the resisting means to permit objects in the till to fall into the vault.

3. In a remote control depositing money container, a till, a vault positioned substantially below the till, a plurality of downwardly swingable bottoms for the till, shafts turning with said till bottoms, arms in parallel relationship attached to said shafts at one side of said till bottom and at an angle below that of said till bottom when said till bottom is at its uppermost position, a connecting rod between said arms whereby said shafts and said arms move concurrently, said arms and said till bottoms being gravity urged to a position whereby any objects contained in the till will be released into the vault, 10 means positioned in the vault and engaging one of said arms for resisting movement of said arms into releasing position, said resisting means being movable out of the path of said arm, the path of movement of resisting means diverging 15 from the path of movement of said arm as said resisting means moves away from resisting position, means for constantly urging said resisting means through its path into releasing position, a fusible link adapted to be weakened past the 20 breaking point by the passage of electricity therethrough, said link normally preventing movement of said resisting means from its resisting position, whereby an electric current may be utilized to release the resisting means to permit objects in the till to fall into the vault.
